SERVICE T FITTING

William M. Jackson, Allentown, Pa., assignor to Bonney
Forge & Tool Works, Allentown, Pa., a corporation
of Pennsylvania

Application May 8, 1958, Serial No. 50,829

Term of patent 14 years

(Cl. D91—3)

Figure 1 is a side elevational view of a service T fitting showing my design;

Figure 2 is an end elevation thereof;

Figure 3 is a top plan view thereof; and

Figure 4 is a perspective view thereof.

I claim:

The ornamental design for a service T fitting, as shown.
